TOY BALLOON SPACE STATION

Robert A. Wolfe, 455 Elizabeth Ave., Newark, N.J.

Filed Apr. 17, 1964, Ser. No. 79,541

Term of patent 14 years

(Cl. D34—15)

FIG. 1 is a frontal perspective view of a toy balloon space station showing my new design; and

FIG. 2 is a rear perspective view of the toy balloon space station of FIG. 1.

The dominant features of my design reside in the portions shown in full lines.

I claim:

The ornamental design for a toy balloon space station, as shown and described.
